RESPIRATOR

Elif A. Moore, Clifton, Tex.

Application April 29, 1938, Serial No. 205,068

2 Claims. (Cl. 128—148)

The invention relates to respirators and more especially to a nasal filter or nasal dust stopper.

The primary object of the invention is the provision of a device of this character, wherein the same is of a construction that it may be inserted into the nostril passages to prevent on inhalation the flow of dust or other foreign floating particles into the nostril passages for relieving sufferers of asthma, hay-fever and sinus disturbances, and being invisible when inserted within the nostril passages.

Another object of the invention is the provision of a device of this character, wherein the same is of a construction to allow tight fitting in the nostril passages for excluding dust and foreign matter therefrom and thus assuring health and comfort, particularly to sufferers of sinus trouble, asthma, colds or other nasal disturbances which cause irritation thereto, the device being of novel construction in its entirety.

A further object of the invention is the provision of a device of this character, wherein the construction thereof enables the application of medicaments to the nasal passages for the treatment of diseases thereof so as to relieve suffering and minimizing the chances of contracting colds or other nasal disturbances.

A still further object of the invention is the provision of a device of this character, which is simple in construction, thoroughly reliable and efficient in operation, readily and easily applied and removed, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a view of the device constructed in accordance with the invention applied to a nasal passage for use.

Figure 2 is an enlarged vertical sectional view through the device.

Figure 3 is a sectional view taken on the line 3—3 of Figure 2 looking in the direction of the arrows.

Figure 4 is a perspective view of one of the wire reinforcements of the device.

Figure 5 is a plan view thereof.

Similar reference characters indicate corresponding parts throughout the several views in the drawing.

Referring to the drawing in detail, the device constituting the present invention comprises a body unit 10 preferably made from rubber rendering the said body inherently resilient or flexible to the required degree for the proper fitting thereof within a nasal passage 11, being of substantially elliptical shape effecting a correspondingly shaped open center 12 while embedded within the body 10 is a reinforcing wire 13 of zigzag formation, being trained spirally through the body 10 with the ends of this wire meeting the outermost coils thereof, the coils of such wire being spread with respect to each other. The wire 13 is embedded in the body 10 and the zigzag formation 14 of this wire assures a freer flexibility or distortion of the body while the spiral arrangement thereof serves to hold the said body distended in a longitudinal direction. The flexibility of the body assures the fitting thereof within the nasal passage 11 for the wearing of the respirator. 20 Several other wires 13' of similar formation to the wire 13 are embedded in the body 10 to be disposed opposite each other and the terminals 15 of these wires are bent inwardly to protrude from the body into the open center 12, which 25 latter affords a cavity or cell for a purpose presently described.

At one end of the body externally thereof is a bead 16 which becomes seated in the wall of the nasal passage 11 for the sealing of the body 30 10 when inserted within this passage to avoid escape of air between the walls of the passage and the exterior surface of said body during respiration by a wearer of the device.

Fitted with the end of the body 10 having the 35 external bead 16 is a concavo-convex wire mesh shield or screen 17, the concavo-convex formation of the latter allows flexing of the body 10 at the longer sides thereof in its elliptical formation. The elliptical formation of the body 10 40 corresponds to the formation of the passage 11 in the nose 18 of a wearer.

Filling the cavity or space 12 created by the opening in the body 10 is an absorbent or filter mass 19 such as lamb's wool, loose cotton batting 45 or other equivalent fibrous material effective for filtering purposes. This mass 19 is retained in the cavity or recess 12 by the terminals 15 of the wires 13' as such terminals function as anchoring means for the mass. It is found desirable that 50 when the mass 19 is within the cavity or recess 12 in the body 10 that it be saturated with a light oil or with suitable liquid medicament so as to assure the collecting of dust or other foreign matter by such mass during respiration when wearing 55

the device. The medicament may be of the kind for the treatment of nasal troubles such as common colds, sinus affliction, hay-fever, asthma or other disturbances.

5 In applying the device, the bead 16 is innermost of the body 10 when within the passage 11 in the nose 18 and not only seals the device between the body 10 and the wall of the passage but also anchors the same when worn within such 10 passage. Breathing by a wearer is had through the nasal passage in the usual manner and dust and other foreign matter will be excluded from the passage 11.

It is of course understood that each passage 11 in the nose 18 is fitted with the device so that protection will be had to both nasal passages and such device is most advantageous for persons working in a dusty or a smoky atmosphere for the exclusion thereof from the nasal passages, the 20 device being beneficial to sufferers of disturbances hereinbefore set forth.

What is claimed is:

1. A device of the character described comprising a tubular inherently yieldable body of substantially elliptical shape in cross section, a concavo convex strainer centered within the body at one end thereof, a reinforcing member spirally embedded in the body, oppositely arranged reinforcing members within said body and having ends projecting inwardly from within the body, and filtering means within the body and anchored by said ends. 10

2. A device of the character described comprising a tubular inherently yieldable body of substantially elliptical shape in cross section, a concavo convex strainer centered within the body at one end thereof, a reinforcing member spirally 15 embedded in the body, oppositely arranged reinforcing members within said body and having ends projecting inwardly from within the body, filtering means within the body and anchored by said ends, and an external bead formation on 20 said body next to the strainer.
